UNITED STATES PATENT OFFICE.

JOSEPH G. BAIN, OF PITTSBURGH, AND LASZLO M. STEMPLE, OF DORMONT, PENNSYLVANIA, ASSIGNORS TO LEWIS FOUNDRY & MACHINE COMPANY, OF PITTSBURGH, PENNSYLVANIA, A CORPORATION OF PENNSYLVANIA.

BRIDLING APPARATUS.

Application filed March 29, 1922. Serial No. 547,754.

To all whom it may concern:

Be it known that we, JOSEPH G. BAIN and LASZLO M. STEMPLE, both citizens of the United States, residing, respectively, at 5 Pittsburgh, in the county of Allegheny and State of Pennsylvania, and Dormont, in the county of Allegheny and State of Pennsylvania, have invented a new and useful Improvement in a Bridling Apparatus, of 10 which the following is a specification.

This invention relates to a bridling apparatus for use in conjunction with rolling mills.

A general object of the invention is to 15 provide bridling apparatus which is simple and compact, and which avoids the difficult and laborious operation of threading a strip being passed to the reducing rolls through stationary bridle bars.

20 A more specific object of the invention is to provide a bridling apparatus of the nature noted above which places a strip being rolled under a tension which may be regulated with respect to the material and thickness of the strip.

25 A further specific object of the invention is to provide such bridling apparatus which places the strip under sufficient tension without producing a rubbing of the metal of the strip against itself or any other metal; this 30 feature rendering the apparatus of particular advantage for use in conjunction with the rolling of aluminum, and other metals the surfaces of which are subject to injury 35 when dragged over a metallic surface.

In the accompanying drawings Figure 1 is a front elevation of the apparatus of the present invention; Figure 2 is a plan view thereof; Figure 3 is a side elevation of the 40 apparatus; and Figure 4 is a cross sectional view therethrough on the line 4—4 Figure 2.

The apparatus comprises primarily a base 1 arranged to be bolted or otherwise secured to the housing of the rolling mill, uprights 45 or housings 2 and 3 secured to the base, and superimposed bridling rolls 4, 5, and 6 mounted in the housing members 2 and 3.

The general principle of the device consists in utilizing the gripping action of the 50 bridling rolls upon a strip passing through the rolling mill for placing the strip passing through the reducing rolls under tension; in adjusting the bridling rolls vertically to

effect this gripping action upon strips of various widths; and in driving one of the 55 bridling rolls positively during the early stages of a bridling operation to actuate all of such rolls for passing the strip to the rolling mill until such strip is gripped by the reducing rolls thereof. 60

The uppermost bridling roll 4 of the three such rolls shown has stationary bearings 7 in the housings 2 and 3; while the intermediate roll 5 and lowermost roll 6 are rotatably mounted by means of their respective trunnions 8 and 9 in bearing blocks 10 and 11 which are vertically movable in these housings. As indicated above, the uppermost roll 4 may be positively driven and the vertical position of the other rolls adjusted, 70 by separate means provided for each of these purposes.

In initially feeding a strip of metal to the reducing rolls, the strip 12 is introduced between the lowermost bridling roll 6 and the 75 intermediate roll 5. The strip 12 is then passed around the intermediate roll 5, between it and the uppermost roll 4, and over the uppermost bridling roll to the reducing rolls. During this threading operation the 80 uppermost roll is preferably driven slowly, and serves also to drive the remaining rolls of the set.

In order to provide a yielding means of contact between the several rolls of the set 85 and the strips 12, and to guide a strip through the bridling rolls, a plurality of belts 13 are passed around and between the rolls. These belts 13 lie between the strip 12 being rolled and the rolls 6 and 4, the strip 90 being in direct contact with the intermediate roll 5 only. The belts 13 also pass over a tightening bar 14, which is mounted in yokes 15 slidable in the housings 2 and 3 and horizontally adjustable therein by means of set 95 screws 16.

When the strip has been threaded through the auxiliary rolls, the lower bridling rolls 5 and 6 may be adjusted vertically to clamp the strip with increased firmness between 100 the rolls of the set.

The means for adjusting the bridling rolls vertically comprise primarily the stiff flat spring 17, which bears directly against the bearing blocks 11 of the lowermost roll 6. 105 Against this spring 17 bears a vertical pin

18, which passes through a bracket 19 forming part of the base 1, and against which bears a lever arm 20 pivoted in the base. This lever arm 20 has a connection 21 with 5 an arm or link 22 connected with an operating handle 23. This operating handle 23 is in turn arranged to cooperate with a toothed segment 25 in such manner that the means acting upon the spring 17 may be locked in 10 proper position to place the spring under the desired compression.

With the rolls 5 and 6 adjusted to clamp the strip 12 firmly with the assistance of the belts 13, the positive actuation imparted to 15 the uppermost roll 4 may be discontinued and the pull of the reducing rolls relied upon for drawing the strip through the bridling rolls.

The means for imparting the positive actuation to the uppermost bridling roll at 20 will comprise an extended trunnion 26 on this roll, such trunnion having an outboard bearing 27 in an upright or standard 28. This extended trunnion or shaft 26 may 25 be connected or disconnected by means of a clutch 29 with a pulley 30 for receiving power from any suitable source, preferably from the rolls of the rolling mill itself. The clutch mechanism proper for this purpose 30 is secured to the yoke 31 of a bell crank lever 32, which is pivoted at 33 to a bracket arm 34 extending from the standard 28. Bell crank lever 33 is connected with an arm or link 35 which is in turn connected with a 35 pivoted treadle 36, extending into such position that an operator may readily operate the clutch mechanism in conjunction with the operation of the handle 23 for clamping the strip between the bridling rolls.

Whereas it is desirable in rolling strips composed of certain metals that the strip be wrapped upon itself to create a frictional drag against the pull of the rolls, in the case of certain other metals, such as aluminum, the creation of such frictional drag is not only unnecessary but is positively harmful to the surface of the strip. The device of the present invention places a strip being rolled under sufficient tension 45 to prevent curling or warping thereof, without the necessity of wrapping the strip being rolled upon itself in order to provide the proper resistance to the pull of the rolls. The grip of the bridling rolls upon a strip 50 passing therethrough is insured by the belts 13, which provide a yielding filling means between the points of contact of the rolls.

It is also desirable that strips composed 55 of aluminum should not be dragged over any other metallic surface in their passage to the reducing rolls. In this connection it may be noted that a strip passing through the bridling rolls is in direct contact with the belts 13, and is not in direct contact 60 with either the uppermost roll 4 or the low-

ermost roll 6. As the strip does come into direct contact with the intermediate roll 5, this roll may be provided with a felt or fibre covering 37 in order to prevent the strip from coming into contact with the metal of this roll. 70

It will be further noted that the apparatus described above is easy to operate, and that the tension under which a strip is placed during rolling may be readily regulated by adjustment of the two vertically movable rolls. 75

The advantages of the device as hereinabove set forth, together with numerous other advantages, will be readily appreciated by those skilled in the art to which the invention pertains. As the device described and illustrated is, moreover, susceptible of a number of modifications without departing 80 from the spirit of the invention embodied therein, the scope of the invention is to be restricted only by the limitations contained in the claims appended hereto. 85

What we claim is:

1. Bridling apparatus for use in conjunction with rolling mills comprising a set of superimposed bridling rolls, and means whereby one of said bridling rolls may be positively actuated at will or such positive actuation discontinued without discontinuing operation of the set of bridling rolls. 90

2. Bridling apparatus for use in conjunction with rolling mills comprising a set of bridling rolls for receiving and placing under tension a strip passing to the mill, and means on said bridling rolls for increasing the frictional engagement between said rolls and the strip passing therethrough and for preventing direct contact between the metal 95 of said rolls and the surface of the strip. 100

3. Bridling apparatus for use in conjunction with rolling mills comprising a set of superimposed bridling rolls for receiving and placing under tension a strip passing to the mill, and belting passing around and between said bridling rolls providing a frictional engagement between said rolls and the strip passing therethrough. 110

4. Bridling apparatus for use in conjunction with rolling mills comprising a set of superimposed bridling rolls for receiving and placing under tension a strip passing to the mill, belting passing around and between said bridling rolls for providing a frictional engagement between said rolls and the strip passing therethrough, and means for driving one of said rolls positively and thereby actuating all the rolls of the set. 115

5. Bridling apparatus for use in conjunction with rolling mills comprising a set of superimposed bridling rolls for receiving and placing under tension a strip passing to the mill, belting passing around and between said bridling rolls providing a frictional engagement between said rolls and 120 125 130

the strip passing therethrough, and adjustable means for maintaining said belting taut.

6. Bridling apparatus for use in conjunction with rolling mills comprising a bridling roll rotatably mounted in stationary bearings, means for positively driving said bridling roll, and a vertically adjustable bridling roll arranged to grip a strip passing 10 to the mill between itself and said positively driven roll, and resilient means arranged to act upon said roll for forcing the same toward said stationary roll.

7. Bridling apparatus for use in conjunction with rolling mills comprising a set of more than two superimposed bridling rolls arranged to have a strip passing to the reducing rolls of the mill threaded therethrough in operative contact with all 20 thereof.

8. Bridling apparatus for use in conjunction with rolling mills comprising a set of more than two superimposed bridling rolls arranged to have a strip passing to the reducing rolls of the mill threaded therethrough in operative contact with all thereof, and means for positively driving one of the bridling rolls of the set.

9. Bridling apparatus for use in conjunction with rolling mills comprising a set of more than two superimposed bridling rolls arranged to have a strip passing to the reducing rolls of the mill threaded therethrough in contact with all thereof, and 35 means for increasing the frictional engagement between said bridling rolls and the strip passing therethrough and for preventing direct contact between the metal of said rolls and the surface of the strip.

40 10. Bridling apparatus for use in conjunction with rolling mills comprising a set of more than two superimposed bridling rolls arranged to have a strip passing to the reducing rolls threaded therethrough in contact with all thereof, means for positively driving one of the bridling rolls, and means for increasing the frictional engagement between said bridling rolls and the strip passing therethrough and for preventing direct 45 contact between the metal of said rolls and the surface of the strip.

11. Bridling apparatus for use in conjunction with rolling mills comprising a set of more than two superimposed bridling rolls 55 arranged to have a strip passing to the reducing rolls of the mill threaded therethrough in operative contact with all there-

of, one roll of said set being mounted in stationary bearings, mounting means for the other rolls of the set arranged to permit vertical adjustment thereof, and resilient means arranged to act upon said rolls for forcing the same toward the stationary roll. 60

12. Bridling apparatus for use in conjunction with rolling mills comprising a set of more than two superimposed bridling rolls arranged to have a strip passing to the reducing rolls of the mill threaded therethrough in operative contact with all thereof, one roll of said set being mounted in stationary bearings, mounting means for the other rolls of the set arranged to permit vertical adjustment thereof, resilient means arranged to act upon said rolls for forcing the same toward the stationary roll, and 70 means whereby the stationary bridling roll may be positively actuated at will and such actuation discontinued without discontinuing operation of the set of bridling rolls. 75

13. Bridling apparatus for use in conjunction with rolling mills comprising a set of more than two superimposed bridling rolls arranged to have a strip passing to the reducing rolls of the mill threaded therethrough in contact with all thereof, means 80 for providing a frictional engagement between said bridling rolls and the strip passing therethrough and for preventing direct contact between the metal of said rolls and the surface of the strip, and mounting means 85 for said bridling rolls arranged to permit vertical adjustment of at least one thereof. 90

14. Bridling apparatus for use in conjunction with rolling mills comprising a set of more than two superimposed bridling rolls 95 arranged to have a strip passing to the reducing rolls of the mill threaded therethrough in operative contact with all thereof, means for positively driving one of the bridling rolls of the set, means for providing a frictional engagement between said bridling rolls and the strip passing therethrough and for preventing direct contact between the metal of said rolls and the surface of the strip, and mounting means for 100 said bridling rolls arranged to permit vertical adjustment of at least one thereof. 105

In testimony whereof, we hereunto set our hands.
